APPARATUS FOR ELECTRICAL
PRECIPITATION

Friedrich Wilhelm Hoss and Walther Deutsch,
Frankfort-on-the-Main, Germany, assignors to
International Precipitation Company, Los An-
geles, Calif., a corporation of California

Application April 19, 1937, Serial No. 137,865
In Germany April 22, 1936

5 Claims. (Cl. 183—7)

The present invention relates generally to improvements for effecting the electrical precipitation of suspended particles from a stream of gas, and more especially to apparatus for this purpose in which the particles are first charged in one field and then precipitated out in a second field. In precipitators of this latter type, the gas is first passed through a discharging or ionizing field in which the particles become electrically charged, and then the gas is passed through a separate substantially non-discharging field in which precipitation of the particles takes place on one or more collecting electrodes.

In electrical precipitators as usually constructed, the gas stream flows past the electrode surfaces in a direction generally parallel thereto, while the electrical field is maintained between the electrodes and so is more or less at right angles to the gas flow. This arrangement is satisfactory for ionizing purposes but in the area of precipitation the gas stream offers little or no assistance to the separation of particles from the gas, but rather interferes with the separation, for there is a tendency to pick up and carry along in the gas stream material that has been previously deposited.

It is a general object of our invention to increase the efficiency of a precipitator of the kind described and especially to increase the effectiveness of the precipitation field in bringing about complete separation of the suspended particles from the gas stream.

It is also a main object of our invention to provide a precipitator of the two-field type in which the gas stream and the precipitating field exert their forces in the same direction on the suspended particles and so reinforce each other in effecting precipitation of the particles.

A further object is to provide a precipitator of the two field type in which the precipitating field has a fluid-pervious electrode through which gas passes to bring about intimate contact of the entire gas stream with the electrode and complete precipitation of the suspended particles.

These objects are attained according to our invention by passing the stream of gas, containing suspended particles previously charged electrically, through a non-discharging precipitation field, and maintaining the precipitation field in such a direction that the force it exerts on the suspended particles generally coincides with the direction of stream flow and so aids the movement of the particles toward the collecting electrode.

One form of apparatus embodying the prin-

ciples of the invention includes a discharge electrode, an intermediate fluid-pervious electrode through which gas flows, and a collecting electrode, which may or may not be fluid-pervious. There is also provided means for establishing a high potential ionizing field between the discharge and intermediate electrodes and a separate substantially non-discharging field between the intermediate and collecting electrodes to effect precipitation of the charged particles. The polarity of the intermediate and collecting electrodes relative to each other is such that the precipitating field moves the charged particles in the general direction of the gas flow from the intermediate to the collecting electrode.

How these and other objects and advantages of our invention are attained will be better understood by reference to the following description and the annexed drawing, in which:

Fig. 1 is a vertical section through a preferred form of precipitator, illustrated somewhat diagrammatically, with suitable electrical equipment also indicated diagrammatically;

Fig. 2 is a horizontal section on line 2—2 of Fig. 1;

Fig. 3 is a fragmentary vertical section through a variational form of precipitator; and

Fig. 4 is a horizontal section upon line 4—4 in Fig. 3.

The form of precipitator illustrated in Figs. 1 and 2 comprises an external housing 10 which is preferably circular in cross-section and is provided with a trap door 12 at the bottom through which precipitated material can be periodically removed. The housing 10, which serves as a collecting electrode, is of sufficiently extended surface and small surface curvature to substantially preclude corona discharge therefrom. Fluid-pervious intermediate electrode 14 is placed within and concentrically of the housing and is supported upon insulators 15 which electrically insulate the electrode from the housing. Electrode 14 is shown as made of perforated plate, but it may be made of wire screen or any other similar material that allows free passage of the gas through the electrode and is of sufficiently extended surface and low surface curvature to substantially preclude corona discharge therefrom. Intermediate electrode 14 is closed at its upper end by plate 16 which also serves as a support for insulator 18 by means of which discharge electrode 20 is mounted axially of the intermediate electrode. The discharge electrode is a wire or small diameter rod and is provided at its lower end with tensioning means, such as weight 21.

Gas is introduced into the precipitator through inlet pipe 24 which discharges upwardly from nozzle 25 into the lower end of intermediate electrode 14. The gas passes through the openings 5 in the intermediate electrode and is discharged from the precipitator through the open upper end 26 of housing 10. Although the lower end of electrode 14 may be closed by means of a non-conducting member, which will insulate the electrode 10 from gas nozzle 25, this is not necessary with the construction illustrated. The gas, issuing from nozzle 25 at a relatively high velocity, is projected into the upper portion of the electrode, and by constricting the open lower end of 15 the electrode around nozzle 25, substantially no gas escapes from the electrode at this point.

The electrical equipment may be varied as desired to suit operating requirements. As typical of a preferred arrangement, but without limitation thereto, we show means for supplying the precipitator with rectified high tension alternating current. After the alternating current is stepped up by transformer 30, it is passed through a full wave rectifier 31 so that unidirectional current is supplied to discharge electrode 20 by leads 32 and 33. A voltage divider 34 is included in the circuit so that current at a lower voltage may be supplied to intermediate electrode 14 by lead 35. It will be realized that 30 there may be employed a separate source of electric power for each of the discharge and intermediate electrodes, instead of the single source shown.

Housing 10 is connected with the ground at 38 so that, with respect to it, electrodes 14 and 20 are both of the same polarity. The potential applied to discharge electrode 20 is sufficiently great to produce the well known corona or silent discharge from it, but not sufficient to bring 40 about a disruptive or spark discharge. A lesser potential is applied to electrode 14 than that applied to the discharge electrode and, electrode 14 being without sharp corners or projections of small radius which would promote the formation 45 of corona discharge, there is maintained in the annular space between electrode 14 and housing 10 a substantially non-discharging electrical field. It is preferred, but not necessary, that discharge electrode 20 be charged negatively and consequently electrode 14 is also negative with 50 respect to housing 10 but is positive with respect to the discharge electrode.

The gas issuing from nozzle 25 first reaches the discharge electrode and travels parallel to it, 55 bringing the suspended particles into the ionizing field where they become charged negatively, that is of the same polarity as the charge of electrode 20. The flow of gas is then radially outward through the openings in electrode 14 and 60 the charged particles, being repelled by electrode 20, are moved by the electric field in the same direction. The gas and suspended particles after passing through fluid-pervious electrode 14, enter 65 the precipitating field maintained in the annular space around electrode 14. The charged particles are then in a strong field of such polarity that they are repelled by electrode 14, the direction of the field moving them toward housing 10 which acts as a collecting electrode upon 70 which the particles are precipitated when they come in contact therewith and lose their charge. The direction of gas movement through the intermediate fluid-pervious electrode is radially outward in the same direction as the movement of 75 particles induced by the precipitating field, so

that the gas movement and the field reinforce each other. Thus both the ionizing and precipitation fields are of a polarity to reinforce the gas stream in moving suspended particles. The cleaned gas is then deflected upwardly and discharged from the open upper end of housing 10.

Figs. 3 and 4 disclose a variational form of precipitator in which the discharge, intermediate and collecting electrodes are mounted in planes across flue 40, typically rectangular in cross-section. The discharge electrodes 20a are mounted in a rectangular frame 41 supported from the top of the flue on insulators 42. Fluid-pervious intermediate electrode 14a is likewise mounted on a rectangular frame and supported from insulators 43. Insulators 42 and 43 electrically insulate the discharge and intermediate electrodes from each other and from flue 40 which is grounded at 36. Collecting electrode 45, herein shown as a fluid-pervious member made 20 of wire screen or the like, is supported directly from the flue walls and is electrically connected therewith. The electrical connections 33 and 35 are the same as described in Fig. 1 and respectively supply high tension unidirectional current 25 to the discharge and intermediate electrodes.

The electrodes are so arranged that the gas stream moving toward the right, as indicated by the arrow in Fig. 3, will encounter successively the discharge, the intermediate and then the collecting electrode. The gas first passes through an ionizing field maintained between electrodes 20a and 14a, in which field the particles suspended in the gas become charged electrically with the same polarity as the discharge 35 electrodes. The gas stream with its charged particles then moves through the fluid-pervious intermediate electrode 14a and enters the non-discharging field maintained between electrodes 14a and 45, in which the polarity of the electrodes is such that the suspended particles are 40 moved in the direction of stream flow toward the collecting electrode 45. It will be noted that the mode of operation and electrode arrangement are the same as described in connection 45 with Fig. 1, except that in the present form both the intermediate and collecting electrodes are fluid-pervious.

Apparatus in which the ionizing field is spaced from the precipitating field by a substantial distance, as by replacing the intermediate electrode by two individual electrodes so that the ionizing field is maintained between one pair of electrodes and the precipitating field between a separate second pair, is described and claimed in our copending application Serial No. 137,864, filed April 19, 1937, which application also broadly claims the apparatus and the method of operation embodied in both applications. Since various changes in the shape, arrangement and application of the various parts of our invention may be made without departing from its true spirit and scope, the description and drawing are to be construed as illustrative of rather than restrictive upon the appended claims.

We claim:

1. In an electrical precipitation apparatus through which flows a stream of gas containing suspended particles to be removed, the combination of a discharge electrode; an intermediate fluid-pervious electrode through which gas flows; a collecting electrode; said three electrodes being arranged successively in the path of gas flow; and means for establishing an ionizing field between the discharge and intermediate electrodes, and a separate substantially non-discharging 75

precipitating field between the intermediate and collecting electrodes, the precipitating field being of such direction as to reinforce gas flow from the intermediate to the collecting electrode for collection thereon of suspended particles.

5. 2. In an electrical precipitation apparatus through which flows a stream of gas containing suspended particles to be removed, the combination of a discharge electrode; an intermediate 10 fluid-pervious electrode through which gas flows; a collecting electrode; said three electrodes being arranged successively in the path of gas flow; and means for establishing an ionizing field between the discharge and intermediate electrodes, 15 and a separate substantially non-discharging precipitating field between the intermediate and collecting electrodes, the polarity of the discharge and intermediate electrodes being the same, relative to the collecting electrode, with a potential drop between the discharge and intermediate electrodes.

3. In an electrical precipitation apparatus through which flows a stream of gas containing suspended particles to be removed, the combination 20 of a discharge electrode; a fluid-pervious intermediate electrode through which gas flows; a fluid-pervious collecting electrode through which gas flows; said three electrodes being arranged successively in the path of gas flow; and 25 means for establishing an ionizing field between the discharge and intermediate electrodes, and a separate substantially non-discharging precipitating field between the intermediate and collecting electrodes, the precipitating field being 30 of such direction as to reinforce gas flow from the intermediate to the collecting electrode for collection thereon of suspended particles.

4. In an electrical precipitation apparatus through which flows a stream of gas containing suspended particles to be removed, the combination of a discharge electrode; a hollow intermediate fluid-pervious electrode through which gas 5 flows, surrounding the discharge electrode; a hollow collecting electrode surrounding the intermediate electrode; said three electrodes being arranged successively in the path of gas flow; and means for establishing an ionizing field between the discharge and intermediate electrodes, 10 and a separate, substantially non-discharging precipitating field between the intermediate and collecting electrodes, the precipitating field being of such direction as to reinforce gas flow 15 from the intermediate to the collecting electrode for collection thereon of suspended particles.

5. In an electrical precipitation apparatus through which flows a stream of gas containing suspended particles to be removed; the combination 20 of a discharge electrode; an intermediate fluid-pervious electrode through which gas flows; a collecting electrode; said three electrodes being arranged successively in the path of gas flow; and means for establishing an ionizing field between the discharge and intermediate electrode, 25 and a separate substantially non-discharging precipitating field between the intermediate and collecting electrodes, both the ionizing and the precipitation fields being of such polarity as to 30 move particles in the same direction to reinforce gas flow through the intermediate pervious electrode.
